SLUG AND APERTURE FOR CHECK
CONTROLLED APPARATUSOscar H. Goetz, Park Ridge, Ill., assignor to Yale
Slot & Slug Company, Chicago, Ill., a corpora-
tion of Illinois

Application October 13, 1933, Serial No. 693,483

6 Claims. (Cl. 194—4)

The present invention relates to improvements in slugs and slug receiving apertures for check controlled apparatus, such as telephone pay stations, etc.

- 5 One of the principal objects of the invention is to provide an improved combination of slug and aperture which are of such construction as to enable the conventional coin box to be instantly converted for slug use, without having to perform the tedious, laborious operations heretofore required in effecting such conversion. In the conventional telephone coin box, the upper ends of the coin chutes are usually covered by a housing which has circular pockets or apertures opening into the front face of the housing, one of such pockets or apertures being provided for each chute. The coins are inserted into such apertures flatwise, and are then pushed back into the housing until they are in position to drop down through the respective chutes. In converting this type of box into one capable of operation only by slugs, it has heretofore been necessary either to perform riveting or like operations in fastening wards or guards in the form of pins, ribs, etc. within the apertures, or to provide a supplementary front housing having coded top slots for edgewise insertion of grooved slugs, or to provide an entirely new, specially constructed housing adapted to fit over the upper ends of the coin chutes. Each of these operations represents a relatively expensive laborious installation. Furthermore, in the event that it is desired to change the coded arrangement of the slug and aperture, the difficulties of this operation are repeated.
- 35 In the practice of my invention, it is only necessary to press a ring into the front of the aperture which is to be converted for slug usage. This ring can be instantly pressed into place by a simple hand tool. In the event that it is desired to change the coded arrangement, this ring is forced out of the aperture and a differently coded ring pressed into its place.

Another object of the invention is to provide an improved slug and aperture which are both of substantially symmetrical shape, whereby the slug can be inserted through the aperture with the periphery of the slug in practically any angular position with respect to the periphery of the aperture. That is to say, it is not necessary to turn the slug to bring some one angular point of its periphery into registration with some one angular point of the aperture, but, instead, the slug can be pushed through the aperture without necessitating the conscious effort of bringing wards or recesses on the slug into registration with

wards or recesses in the aperture. This is accomplished by utilizing substantially the entire periphery of the slug and of the aperture in effecting the coded arrangement. In the preferred embodiment of the invention, the periphery of the slug is formed with uniformly spaced teeth and the periphery of the aperture is also formed with uniformly spaced teeth, the slug and aperture registering when the teeth of the slug match with the tooth spaces or pockets of the aperture. It will be evident that this toothed formation does not require any particular top, bottom or side point of the slug being brought into registration with any particular top, bottom or side point of the aperture, but the slug can be pushed through the aperture in a multiplicity of different positions. The toothed formation is also readily adaptable to a large number of changes in the coded arrangement, inasmuch as the mere addition or subtraction of one or two teeth from the total number of teeth of the slug and the total number of teeth of the aperture will result in an entirely different coded arrangement.

Another object of the invention is to so shape one set of teeth that the other set of teeth is automatically centered or registered with the tooth spaces of the first set of teeth in the mere act of pushing the slug into and through the aperture. In the preferred construction, this is accomplished by forming the front or outer ends of the teeth in the aperture of a tapered or wedge shape so that the sloping surfaces of the tapered teeth in the aperture automatically deflect the teeth of the slug into proper registration with the tooth spaces of the aperture.

While my invention has its principal utility in connection with telephone pay stations, it will be understood that it also has utility in connection with vending machines and other coin or slug controlled apparatus.

Other objects and advantages of the invention will appear from the following detail description of a preferred embodiment thereof. In the accompanying drawing illustrating such embodiment:—

Figure 1 is a front elevational view of a typical telephone pay station showing my invention associated with one of the coin receiving apertures;

Figure 2 is a fragmentary front elevational view on a larger scale, showing the coin receiving housing which is mounted on top of the coin box, and illustrating my improved attachment ring inserted within one of the coin receiving apertures;

proximately on the plane of the line 3—3 of Figure 2;

Figure 4 is an elevational view, partly broken away, of this attachment ring;

5 Figure 5 is a fragmentary perspective view of the attachment ring, as viewed from the inside of the ring, and serving to show the tapered or sloping surfaces of the teeth within the aperture; and

10 Figure 6 is a front elevational view of the improved slug.

The telephone pay station illustrated in Figure 1 comprises the usual coin receiving box 8 having one or more coin chutes opening into the top of the box, one of such chutes being indicated at 9 in Figure 3. The upper ends of the chutes are covered by a coin receiving housing 11 having the apertures 12, 13 and 14 in the front face thereof. Each aperture opens into a downwardly extending passageway or chute which is substantially coextensive with the corresponding coin chute in the box 8, one of these upper passageways being indicated at 15 in Figure 3. A small hole 16 is usually provided to open into each chute passageway 15 through the back wall of the housing 11. The housing 11 is intended to represent any typical or standard construction of coin receiving housing mounted on the coin receiving box 8. Such housing may be a unitary casting, or may consist of front and back sections riveted together. In ordinary practice, this housing has base flanges or ears 17 which are riveted to the top of the box 8, and frequently has depending lugs 18 adapted to register with openings in the top of the box. Numerals appearing through the apertures 12, 13 and 14 designate that these apertures are for receiving 5¢, 10¢ and 25¢ coins, respectively. It is the customary practice to convert only the 5¢ aperture 12 to slug use, and accordingly I shall describe my invention in connection with this aperture, although it will be understood that the invention may also be adapted to the other aperture 13.

In adapting this aperture to the reception of slugs, I merely press a specially constructed ring 21 into the aperture. This ring is preferably a sheet metal stamping comprising the annular wall portion 22 and an outwardly diverging annular rim or flange 23 on the front or outer end of the ring. The wards or guards of the ring consist of uniformly spaced teeth or like projections 24 punched to extend inwardly from the annular body 22 of the ring. As best shown in Figure 5, the tooth-like projections 24 are punched or formed on a taper so that the two side wall surfaces 24' of each projection converge forwardly toward each other, terminating substantially in a point which merges with the annular body portion 22. These surfaces 24' function as deflecting surfaces for directing the tooth projections on the slug into proper registration with the tooth spaces 25 between alternate teeth 24.

The ring 21 is preferably of such size as to have a driven or forced fit within the aperture 12. The inserting operation can be performed by a suitable hand clamping tool or by a small driving tool. The entering end of the aperture 12 is ordinarily provided with a beveled edge 28. The beveled rim 23 of the ring 21 is forced against this beveled edge 28 and serves to limit the distance that the ring can be forced into the aperture. It will also be noted that the beveled surface 23 of said ring is forward of the tooth projections 24, where it aids in centering the slug and properly directing the slug as the latter is pushed rearwardly into

and through the aperture of the ring. The depth of the ring is such as to dispose its rear edge short of the downwardly extending passageway 15 so as not to interfere with the downward movement of the slug through this passageway. When the ring is in position within the aperture 12, it defines a toothed aperture 12a therein which will only receive a correspondingly shaped slug.

5 The slug is indicated at 31 in Figure 6. Formed around its periphery are the uniformly spaced teeth or projections 34 with alternating tooth spaces or recesses 35. These tooth projections and tooth spaces have a relatively close matching fit with the tooth spaces 25 and tooth projections 24 in the aperture 12a. In inserting the slug it is merely placed flatwise within the front end of the toothed aperture 12a and is then pressed back through the aperture with the finger. Should the tooth projections 34 of the slug be out of registration with the tooth spaces 25 of the aperture when the slug is presented into the aperture, the sloping surfaces 24' of the tooth projections in the aperture automatically center or align the projections 34 with the tooth spaces 25. Also, because of the uniform, symmetrical spacing of the tooth projections on the slug and of the tooth spaces in the aperture, there is no need of having to align any top, bottom or side point of the slug with any corresponding top, bottom or side point of the aperture. This makes the use 10 of the slug much more simple and convenient. A wide variety of coded arrangements can be obtained by merely increasing or decreasing the total number of tooth projections around the slug and the total number of tooth spaces within the 15 aperture; or, as an alternative method, either alone or in combination with different members of tooth projections and tooth spaces, the tooth projections 24 in the aperture might be made 20 higher and the tooth spaces 35 in the slug made 25 correspondingly deeper.

Should it be desired to substitute a differently coded ring 21, the old ring can be withdrawn either by inserting a tool through the hole 16 from the back side of the housing 11 and forcing the ring out of the aperture 12, or by inserting a grasping tool through the front side of the ring and effecting a hooked engagement with the back edges of the tooth projections 24 for pulling the ring outwardly.

50 Numerous modifications and rearrangements may be made without departing from the essence of my invention. For example, in lieu of retaining the ring 21 in the aperture 12 by a drive fit, it may be held in place by suitable locking or detent parts or mechanism which can only be released by authorized persons. Furthermore, instead of forming the toothed aperture 12a by the insertion of the ring 21 into the aperture 12, the tooth projections 24 and tooth spaces 25 might be 55 cast or formed as an integral part of the member defining the aperture 12.

Attention is directed to the fact that the toothed aperture 12a is incapable of passing a 5¢ coin, or of passing such coded slugs as have heretofore been used. These prior slugs, having either radially extending slots, grooved faces or other coded arrangements, are of substantially the same size as a 5¢ piece and cannot pass through the relatively small diameter defined between the high points of substantially opposite tooth projections 24 within the aperture 12a. At the same time, my invention does not require that the authorized slug 31 be of objectionably small size. The standard aperture 12 in the housing 11 is 70 75

somewhat larger than a 5¢ coin, and the annular wall 22 of the ring 21 is relatively thin. Hence, the slug which will pass through this ring can be made of a size approaching within a few thousandths 5 of an inch the size of a 5¢ coin. Such a slug will be efficacious to close circuit controlling contacts or to release locking or tripping mechanism in the same manner as a 5¢ coin. Should it be desirable to use a slug of the same size as the coin, 10 it is only necessary to ream out the standard aperture 12 to a few thousandths of an inch larger diameter and to use a correspondingly larger ring 21. Similarly, where the tooth projections 24 and tooth spaces 25 are cast integral 15 with the housing 11, the size of the toothed aperture may be such as to accommodate a slug having the same over-all diameter as the coin. The height of the tooth projections 24 within the aperture 12a may be made greater or less as desired 20 (with corresponding change in the depth of the recesses 35 in the slug); in the preferred arrangement being such that any smooth surface token or slug which is capable of passing through the small diameter or small circle defined between 25 the high points of these projections 24 will be incapable of closing the circuit controlling contacts or of releasing the locking or tripping mechanism of the coin receiving box.

I claim:

30 1. The combination with a housing including a chute, of an aperture communicating with said chute and adapted to have slugs passed therethrough for entry into said chute, said aperture having substantially uniformly spaced recesses 35 arranged peripherally around the inside of said aperture and having an annular beveled surface forward of said recesses for guiding slugs into the recessed portion of said aperture, and a slug having substantially uniformly spaced projections 40 arranged peripherally around the outside of said slug adapted to register with said recesses when said slug is passed through said aperture.

2. The combination with a housing including a chute, of an aperture communicating with said chute and adapted to have slugs passed therethrough for entry into said chute, said aperture having substantially uniformly spaced recesses arranged peripherally around the inside of said aperture, said recesses tapering to decrease 45 in width from the front to the back of said aperture, and a slug having substantially uniformly spaced projections arranged peripherally around the outside of said slug adapted to register with said recesses when said slug is passed through 50 said aperture.

3. The combination with a housing including a chute, of an aperture communicating with said chute and adapted to have slugs passed therethrough for entry into said chute, said aperture having alternating tooth projections and tooth spaces 5 arranged peripherally around the inside of said aperture, said tooth projections tapering in width to have relatively narrow ends at the front side of said aperture, and a slug having alternating tooth spaces and tooth projections 10 arranged peripherally around the outside of said slug adapted to register with the tooth projections and tooth spaces of said aperture when said slug is passed through said aperture.

4. The combination with a housing including 15 a chute and including an aperture through which slugs are to be passed for entry into said chute, of a ring inserted in said aperture having substantially uniformly spaced recesses formed around the inner periphery of said ring and having an annular beveled surface forward of said recesses for guiding slugs into the recessed portion of said ring, and a slug having substantially uniformly spaced projections arranged peripherally around the outside of said slug adapted 20 to register with said recesses when said slug is passed through said ring.

5. The combination with a housing including a chute and including an aperture through which slugs are to be passed for entry into said chute, 30 of a ring for insertion in said aperture having substantially uniformly spaced recesses formed around the inner periphery of said ring, said recesses tapering to decrease in width from the front to the back of said ring, and a slug having 35 substantially uniformly spaced projections formed around the outer periphery of said slug adapted to register with said recesses when said slug is passed through said ring.

6. The combination with a housing including 40 a chute and including an aperture through which slugs are to be passed for entry into said chute, of a ring for insertion in said aperture having alternating tooth projections and tooth spaces 45 formed around the inner periphery of said ring, said tooth projections tapering in width to have relatively narrow ends adjacent to the front side of said ring, and a slug having alternating tooth spaces and tooth projections formed around the 50 outer periphery of said slug adapted to register with the tooth projections and tooth spaces of said ring when said slug is passed through said ring.

OSCAR H. GOETZ. 55
